(57) **CLAIM**

The ornamental design for a sunglass rack, as shown and described.

DESCRIPTION

FIG. 1 is a perspective view showing our new design for a sunglass rack,

FIG. 2 is a front view thereof,

FIG. 3 is a rear view thereof,

FIG. 4 is a left side view thereof,

FIG. 5 is a right side view thereof,

FIG. 6 is a top view thereof,

FIG. 7 is a bottom view thereof; and,

FIG. 8 is a perspective view with an upper part shown in an open position.

The portions shown in dotted lines are for illustrative purposes only, forming no part of the claimed design.

1 Claim, 5 Drawing Sheets
